UNITED STATES PATENT OFFICE

161,366

TELEPHONE HAND SET SHOULDER REST

Milton Paul, Great Neck, N. Y.

Application November 8, 1949, Serial No. 5,931

Term of patent 14 years

(Cl. D26—14)

To all whom it may concern:

Be it known that I, Milton Paul, a citizen of the United States, residing at 8 Woodland Place, Great Neck, Long Island, New York, have invented a new, original, and ornamental Design for a Telephone Hand Set Shoulder Rest, of which the following is a specification, reference being had to the accompanying drawing, constituting a part hereof:

Fig. 1 is a perspective view of a telephone hand set shoulder rest, showing my new design,

Fig. 2 is a top plan view,

Fig. 3 is a front elevational view,

Fig. 4 is a right hand side elevational view,

Fig. 5 is a left hand side elevational view, and

Fig. 6 is a cross sectional view thereof taken on the line 6—6 of Fig. 3.

I claim:

The ornamental design for a telephone hand set shoulder rest, substantially as shown.

MILTON PAUL.
